UNITED STATES PATENT OFFICE.

WILLIAM H. EBELHARE, OF SYRACUSE, NEW YORK, AND JOSEPH A. FREUND, OF WALTHAM, MASSACHUSETTS, ASSIGNORS TO THE KEYSTONE WATCH CASE COMPANY, OF PHILADELPHIA, PENNSYLVANIA, A CORPORATION OF PENNSYLVANIA.

DESIGN FOR A BRIDGE-PLATE FOR WATCH-MOVEMENTS.

42,574.

Specification for Design.

Patented June 4, 1912.

Application filed February 17, 1912. Serial No. 678,910. Term of patent 14 years.

To all whom it may concern:

Be it known that we, WILLIAM H. EBELHARE, a citizen of the United States, and a resident of Syracuse, county of Onondago, and State of New York, and JOSEPH A. FREUND, a citizen of the United States, and a resident of Waltham, in the county of Middlesex and State of Massachusetts, have jointly invented a certain new, original, and ornamental Design for a Bridge-Plate for Watch-Movements, illustrated in the accompanying drawing, which shows a plan view of the bridgework of a watch-movement made in accordance with our design.

What we claim is:—

The ornamental design for a bridge plate for a watch movement, as shown.

WILLIAM H. EBELHARE.
JOSEPH A. FREUND.

Witnesses as to William H. Ebelhare:

ARTHUR J. BRIGGS,
ELAM H. GROFF.

Witnesses as to Joseph A. Freund:

W. C. COOK,
R. SCHMIEDTGEN.
